UNITED STATES PATENT OFFICE.

JEAN ALEXANDRE LACÔTE, OF PARIS, FRANCE.

MACHINE FOR TREATING VEGETABLE-STEMS.

SPECIFICATION forming part of Letters Patent No. 701,057, dated May 27, 1902.
Application filed March 14, 1901. Serial No. 51,109. (No model.)

To all whom it may concern:

Be it known that I, JEAN ALEXANDRE LACÔTE, a citizen of the Republic of France, and a resident of Paris, France, have invented a new and useful Improvement in or Relating to Machines for Treating Vegetable-Stems, which improvement is fully set forth in the following specification.

The present invention relates to a new machine for stripping and preparing vegetable stems, such as ramie-stems and the like, preparatory to spinning.

In order to render the following explanation as clear as possible, a machine according to this invention is represented in the accompanying drawings.

Figure 1 is a part-sectional view in elevation of the machine, one of the lateral brackets being removed in order to show the interior parts. Fig. 2 is a plan view of the machine. Fig. 3 is a side view showing the driving-gear.

The machine comprises two grooved rollers $a a'$. The upper roller a' is mounted in movable bearings b , which can be adjusted by means of screws c . The object of this arrangement is to vary the distance between the two rollers $a a'$.

The vegetable-stems are introduced into the machine over the plate or guide d and pass between the two grooved rollers $a a'$, which in carrying them forward break the wood in the interior of the skin of the stems into small pieces without, however, breaking the external longitudinal fibers. Thence the stems pass between grinders or rubbing devices $e e'$. Each of these devices consists of two end plates with four radiating arms f . The arms of one of the brackets are connected to the corresponding arms of the other bracket by means of rods g , provided with a loose sleeve or tube h , which sleeves are of much greater internal diameter than the diameter of the rods g , so as to "hang" loosely thereon and to be pressed laterally relatively to the rods by the action of the stems passing between the rubbing devices. The sleeves

h of one of the devices extend, as shown in Fig. 1, between two arms of the other grinder, so as to intercalate, and the devices having opposite rotatory movements the sleeves h grind or rub against the vegetable-stems as they rotate, detaching thereby the fragments of broken wood produced by the action of the rollers $a a'$. In this way sliders or crushed stems are obtained, the ligneous parts having been completely removed.

The transmission of movement is effected in the following manner: A pulley i is mounted upon a shaft j , carrying a sprocket-wheel k , over which a chain l passes, which transmits the movement to a pinion m , fixed on the shaft of the inner grinder e' . At the other extremity of this shaft is a spur-wheel o , which engages with a wheel p , fixed on the shaft of the other grinder e , thereby effecting the opposite rotation of the two devices. Moreover, a toothed wheel q is keyed on the main shaft j , which engages with a wheel r , mounted upon the shaft s of the inner roller a . This shaft s carries at one of its ends a toothed wheel x , which engages with a wheel u , mounted upon the shaft of the other roller a' , thus producing the opposite movement of the two grooved rollers $a a'$.

Having now particularly described and ascertained the nature of the said invention and in what manner the same is to be performed, I declare that what I claim is—

In a machine for treating vegetable-stems, a pair of oppositely-revolving rubbing devices, constructed of radial arms connected by parallel rods, and tubes or sleeves of rather greater internal diameter than the rods, and hanging loosely on the same so as to have a certain lateral motion relatively to the rods, substantially as set forth.

In testimony whereof I have signed this specification in the presence of two subscribing witnesses.

JEAN ALEXANDRE LACÔTE.
